[57] CLAIM

The ornamental design for a front housing portion and associated latch element for a laptop computer, as shown and described.

DESCRIPTION

FIG. 1 is a perspective view of a front housing portion and associated latch element for a laptop computer showing our new design;

FIG. 2 is a front elevational view thereof; and,

FIG. 3 is an enlarged fragmentary view thereof.

In FIGS. 1, 2 and 3, the broken lines showing of portions of the computer housing and base pads is for illustrative purposes only and forms no part of the claimed design.
